2,289,676

METHOD FOR THE MANUFACTURE OF
SPARK PLUGS

George M. Paulson, New York, N. Y.

Original application filed August 21, 1940, Serial No. 353,445, now Patent No. 2,280,972, dated April 28, 1942. Divided and this application filed June 12, 1941, Serial No. 397,652.

7 Claims. (Cl. 29—155.51)

This invention is an improved method for the manufacture of spark-plugs and spark-plug core assemblies. The invention relates more particularly, though not necessarily exclusively, to the manufacture of mica-insulated plugs.

Objects are to facilitate and simplify manufacture, and to insure close fits between elements of the core assembly. These and other objects and advantages of the invention, and the manner in which they are realized, will become apparent as the specification proceeds.

This application is a division of application Serial No. 353,445, filed August 21, 1940, now Patent No. 2,280,972, granted April 28, 1942.

In the accompanying drawing, forming a part hereof:

Fig. 1 is a longitudinal sectional view of a spark-plug made by the method of this invention.

Fig. 2 is a sectional view illustrating the method of making the core assembly of the spark-plug shown in Fig. 1.

The spark-plug shown in the drawing has a metal lower body or shell 10 provided with ground electrodes 11, and an upper metal body 12 which threads into the shell 10 and compresses a gasket 13 against the top of the shell. The lower part of this upper body corresponds to what, in spark-plug construction, is sometimes referred to as a coupling nut. An opening 14 through the upper metal body 12 tapers toward its lower end, i. e. the diameter of the opening 14 becomes progressively smaller toward its lower end.

A downwardly tapering spindle 16 has a head 18, constituting a center electrode, welded to its lower end. This head is large enough to form an annular shoulder 19 on the spindle. An insulating sleeve or cigarette 21 of mica insulation, tightly wrapped, is directly interposed between the tapered surfaces of the spindle 16 and the opening 14. This sleeve or cigarette extends from the shoulder 19 to the top of the part 12 of the body of the plug.

An additional body of insulation, preferably consisting of a stack of mica washers 22, is held under compression between the shoulder 19 and a recessed face at the bottom of the body part 12, and closely surrounds the lower portion of the mica cigarette 21.

The spindle 16 preferably consists of a tube 17 of steel or other suitable metal, which tapers both outside and inside, and a tapered insert 23 of copper or other material of relatively high heat conductivity. Such inserts aid in conducting heat away from the center electrode 18, and

the upwardly increasing section of this spindle facilitates heat conduction and radiation.

The upper end of the spindle 16 terminates well below the upper end of the body 12, leaving a shielding barrel 24 at the upper region of the spark-plug, lined by the insulating cigarette 21, to receive an insulated conductor.

The method by which the core assembly is put together during manufacture is partly illustrated by Fig. 2. The core assembly may be said to include the metal body part 12, the spindle 16, or its element 17, the spindle head 18, and the insulation 21 and 22.

An important feature of the method is that the insulation 21, 22 is associated with the spindle, or the spindle element 17 before the head 18 is welded to the spindle, and is in place when the welding operation is performed. This makes unnecessary a subsequent machining operation to remove external flash, or extruded metal, at the junction between the spindle and the spindle head. In former practice, spindle heads were welded to spindles before the insulation was applied, and it was necessary to machine away the flash in order that, thereafter, the insulation might make a good fit with the lower end of the spindle and the shoulder of the spindle head. In the method of this invention the small amount of flash that is formed tends to fill any air space that there may be at this region, and to that extent is beneficial.

The method of assembling and securing the core elements will now be more particularly described, but it will be understood that details may be varied.

The stack of washers 22 is placed in a clamping nut 40, which does not form part of the spark-plug. This nut and the body element 12 are then screwed together, the nut engaging the threads which later connect the body 12 with the lower body or shell 10. The stack of washers is held in position, and is tightly compressed endwise of the stack between a shoulder 50 in the clamping nut and the recessed end face of the body 12. The bore of the stack of washers is taper reamed so that it will fit the tapered cigarette.

The cigarette 21 is tightly wrapped about a mandrel having the same taper as the spindle 16. This mandrel with the cigarette on it is inserted into the tapered opening of the body 12 and the tapered bore of the stack of washers. The mandrel is then removed, leaving the cigarette in place. At a suitable time the ends of the cigarette are trimmed.

Now the hollow spindle element 17 is inserted into the cigarette. The parts are then as shown in Fig. 2. This assembly is placed on an electric resistance welding machine by slipping the spindle element 17 over a tapered electrode 42 of the welding machine. The spindle head 18 is held by a chuck 43, which is the second electrode of the welding machine. One or both of the electrodes of the welding machine move toward and from the other in a manner well understood in the art, and the opening in the end of the clamping nut 40 serves as a guide for accurately positioning the head 18 with respect to the hollow spindle as the two are brought together for welding.

The spindle head is pressed forcibly against the end of the hollow spindle and the current is turned on. The heat and pressure cause metal to flow forming a certain amount of external flash which is accommodated by the mica insulation and helps to close any air space. However, the amount of flash is relatively small, and not sufficient to injure the insulation, since the stack of washers 22 acts as a stop for the head 18 in the welding operation and limits the amount of metal that is extruded. The pressure on the spindle head in the welding operation places some additional compression on the stack of washers, though this need not be the case. In any event the stack is now clamped between the head 18 and the body 12.

The assembly is then removed from the electrode 42, and the nut 40 is removed from the body 12. The stack of washers is then preferably machined to the external taper shown in Fig. 1. The insert 23 is driven into the hollow spindle element 17.

When the body 12 is screwed into the shell 10 the construction of the spark-plug proper is complete.

In former practice it was customary to wrap a mica cigarette about a cylindrical spindle before the cigarette was wrapped. In that operation it was not easy to get a good fit between the lower end of the cigarette and the shoulder of the head. With the method which has been described in this specification the cigarette need not be wound with its end against a shoulder. In the welding operation the shoulder of the head is brought tight against the lower end of the cigarette as well as against the lower end of the stack of mica washers.

Because of the tapered construction the mica cigarette can be more tightly wrapped than the customary cylindrical cigarette, also a tighter fit can be obtained between the cigarette and the bore of the stack of washers. In the core-assembly the cigarette is held tightly between the tapered spindle and the tapered opening in the body 12. It is tight against the washers and tight against the spindle head.

The body of insulation 22 is preferably composed of a stack of mica washers, as herein described. However, the invention, in a broader aspect, is not necessarily limited to this type of insulation, since insulation of other material or construction could be substituted.

Terms of orientation, such as upper and lower, refer to the position of the spark-plug shown in the drawing, not to the position which it may occupy in use. The lower end of the spark-plug is the inward end in relation to the engine cylinder, and the upper end is the outward end.

I claim:

1. In the manufacture of a spark-plug, the

method which comprises associating a spindle, an insulating sleeve about said spindle, a spark-plug body around the upper portion of the sleeve, and a body of insulation around the lower portion of the sleeve and pressed up against the spark-plug body, and with the parts in such assembled relation welding a head to the lower end of the spindle in position to keep the body of insulation on the insulating sleeve and against the spark-plug body.

2. In the manufacture of a spark-plug, the method which comprises associating a spindle, a mica cigarette about said spindle, and a stack of mica washers about the lower part of said cigarette, pressing a head against the lower end of the spindle, cigarette and stack with the cigarette and stack in place on the spindle, and with the head in such position welding the head to the lower end of the spindle.

3. In the manufacture of a spark-plug, the method which comprises associating a spindle, a mica cigarette about said spindle, and a stack of mica washers about the lower part of the cigarette, holding the stack of washers under compression and with the stack so held, pressing a head against the lower end of the spindle and welding the head to the lower end of the spindle in position to keep the stack in place and under compression.

4. In the manufacture of a spark-plug, the method which comprises providing a downwardly tapered spindle and a metal body having a downwardly tapered opening, winding a tapered mica cigarette, providing a body of insulation having a downwardly tapered bore, associating the foregoing elements with said cigarette directly between said tapered spindle and the tapered surface of the opening in said metal body, and said body of insulation about the lower part of said cigarette, and thereafter holding the parts assembled by welding a head to the lower end of said spindle with said body of insulation clamped between said head and the lower portion of said metal body.

5. In the manufacture of a spark-plug, the method which comprises providing a downwardly tapered spindle and a metal body having a downwardly tapered opening, winding a tapered mica cigarette, providing a stack of mica washers having a downwardly tapered bore, associating the foregoing elements with said cigarette directly between said tapered spindle and the tapered surface of the opening in said metal body, and said stack of washers about the lower part of said cigarette, and thereafter welding a head to the lower end of said spindle, the head being brought tight against the lower ends of said cigarette and said stack of washers to hold said stack of washers between said head and the lower portion of said metal body and maintain all of the parts in assembled relation.

6. In the manufacture of a spark-plug, the method which comprises providing a downwardly tapered spindle and a metal body having a downwardly tapered opening, clamping a stack of mica washers against the lower portion of said metal body, taper reaming the bore of said stack of washers, wrapping a mica cigarette on a tapered mandrel, inserting said cigarette into the tapered opening of said metal body and the tapered bore of said stack of washers, inserting said spindle into said cigarette, and thereafter welding a head to the lower end of said spindle.

7. In the manufacture of a spark-plug, the

method which comprises assembling a stack of insulating washers, giving said stack a tapered bore, forming a tapered insulating cigarette on a tapered mandrel, inserting said cigarette into the tapered bore of a metal body, inserting a tapered spindle member into said cigarette, compressing the stack of washers on the tapered cigarette.

rette, and while holding said stack of washers compressed welding a head to the lower end of said spindle member in close contact with the end of said cigarette and in position to keep the stack 5 of washers pressed together after the force compressing the stack of washers is removed.

WASHERS IS REMOVED.
GEORGE M. PAULSON.
